EUGENE T. TURNER, OF NEW YORK, N. Y.

RECTIFYING-DETECTOR FOR WIRELESS SYSTEMS.

1,144,399.

Specification of Letters Patent. Patented June 29, 1915.

Application filed August 22, 1914. Serial No. 858,038.

To all whom it may concern:

Be it known that I, EUGENE T. TURNER, a citizen of the United States, residing in the city, county, and State of New York, have 5 invented certain new and useful Improvements in Rectifying-Detectors for Wireless Systems, of which the following is a specification.

This invention aims to provide an improved detector for wireless telegraph, telephone or other signaling systems of great efficiency, simple in construction, durable and adapted to be very easily and quickly adjusted to the position of maximum efficiency.

The accompanying drawings illustrate an embodiment of the invention.

Figure 1 is a side elevation of a detector showing the principal parts in section; Fig. 2 is a perspective of the same; Fig. 3 is a diagram of a suitable wiring.

Referring now to the embodiment of the invention illustrated, the detector has contact elements A and B, the former being a unitary block or piece of a sensitive material, preferably a crystal of a conducting mineral, and the latter a mass of conducting material finely divided and lying in contact with the crystal. By sensitive material I mean material which is sensitive to alternating current and rectifies the same and which does not have to be in circuit with an electric current like the terminals of the coherers formerly used, but receives and rectifies an alternating current passing in the surrounding ether. These contact elements are carried in a rotatable casing consisting of a ring C of hard rubber or similar non-conducting material, the openings at the sides being closed by cover plates D and E of conducting material, the whole being mounted on pivots F and G constituting the ends of an axis about which the complete casing can be easily and steadily rotated by the finger of the operator. The crystal A is mounted in a bed or matrix H of tin-foil or other suitable conducting material, the face of which is protected from the contact element B by an interposed sheet J of non-conducting material. The finely divided element B may be, for example, an alloy such as aluminum bronze filings, or may be some other suitable metal or may be carbon. The crystal is preferably of the best grade of natural galena.

The supports K and L on which the cas-

ing is pivoted are of conducting material fastened at their lower ends to binding posts M and N mounted on a wooden or other non-conducting base O.

The rotation of the casing C serves to adjust the relation between the crystal and the finely divided element B and to change somewhat the relations between the grains of the finely divided element, so that by 60 turning the casing backward and forward new points of contact can be secured between the two contact elements. There are preferably at all times a great number of points of contact, secured by locating the 65 crystal on the axis of rotation and by the use of a quantity of the finely divided element sufficient to nearly fill the space in which it is confined. The contact elements are tightly housed, practically air tight 70 against atmospheric action. The large radiating surface enables the detector to carry 75 comparatively large currents with no danger of burning out.

In order to prevent or minimize disturbances of the position of the finely divided element by the movement of the table on which the detector is supported a cushioned support is provided consisting of soft rubber feet P fitting with a certain freedom of 80 motion in sockets Q in the underside of the wooden base and having stems R surrounded by spiral springs S in said sockets. The softness of the rubber and the play which is 85 permitted sidewise in all directions as well as vertically relieve the detector to a great 90 extent from vibration and consequent disturbance of the contact.

In use the detector, indicated as a whole by the numeral 2, may be inserted in the 95 circuit in the manner shown in Fig. 3. The aerial wire 3 transmits the impulses received to a transformer comprising a primary 4 and secondary 5, the latter of which is in circuit with the detector. A telephone 100 with ear pieces 6 is inserted in the circuit and the usual fixed condenser 7 and variable condenser 8 are provided. A buzzer 9 is connected to a point in the circuit and is operated by a circuit 10 of its own in which 105 is a key 11. The buzzer is used for testing the detector. With the ear pieces in position the operator works the switch 11 of the buzzer and at the same time adjusts the detector until the noise of the buzzer is heard 110 with the greatest clearness. This is then the best position of adjustment and the ap-

paratus will be used without further attention to the detector for a considerable time.

Though I have described with great particularity of detail a certain specific embodiment of my invention, yet it is not to be understood therefrom that the invention is restricted to the particular embodiment disclosed.

Various modifications in detail and in the arrangement and combination of the parts may be made by those skilled in the art without departure from the invention.

What I claim is—

1. A detector for wireless systems including contact elements one of which is of material sensitive to alternating currents and adapted to rectify them and the other of which is a finely divided conductor having a number of points of contact with said rectifying element.

2. A detector for wireless systems including contact elements one of which is of material sensitive to alternating currents and adapted to rectify them and the other of which is a finely divided conductor having a number of points of contact with said rectifying element, and a rotatable casing carrying said elements and adapted by its rotation to adjust the relation between said elements and secure fresh points of contact of said finely divided conductor with said rectifying element.

3. A detector for wireless systems having two contact elements, one a unitary piece of a material sensitive to alternating currents and adapted to rectify them, and the other a finely divided conductor.

4. A detector for wireless systems having two contact elements, one a unitary piece of a material sensitive to alternating currents

and adapted to rectify them, and the other a finely divided conductor, and a movable casing carrying at least one of said contacts and adapted by its movement to adjust the relation thereof to the other contact, the finely divided conductor engaging the face of the piece of sensitive material to substantially the same extent in all positions of adjustment.

5. A detector for wireless systems having two contact elements, one a unitary piece of a material sensitive to alternating currents and adapted to rectify them, and the other a finely divided conductor and a movable casing carrying said contacts and adapted by its movement to adjust the relation of said elements, the finely divided conductor engaging the face of the piece of sensitive material to substantially the same extent in all positions of adjustment.

6. A detector for wireless systems including a contact element comprising a unitary piece of a material sensitive to alternating currents and adapted to rectify them, and a finely divided contact element housed together in a closed casing so as to be free from atmospheric influence.

7. A detector for wireless systems including a unitary piece of a material sensitive to alternating currents and adapted to rectify them, and a mass of finely divided conducting material in contact therewith.

In witness whereof, I have hereunto signed my name in the presence of two subscribing witnesses.

EUGENE T. TURNER.
